INVENTOR
JOHN HOLTZMAN.
BY
Ronald K. C.
ATTORNEY

UNITED STATES PATENT OFFICE

JOHN HOLTZMAN, OF NEW YORK, N. Y.

SYMMETRICAL RAZOR SHARPENER

Original application filed December 27, 1923, Serial No. 628,888. Divided and this application filed October 8, 1928. Serial No. 311,015.

This invention relates to razor sharpeners of the type adapted to straighten out the teeth or irregularities imparted to the sharpened edge of a razor blade as the result of use in shaving a beard in which type the means for smoothing out the irregularities on the sharpened edge of a blade is a pair of surface hard spheres forcibly held against separation and adapted to engage opposite faces of the sharpened edge of the razor blade.

The object of the invention is to cheapen and standardize the frame construction for mounting a pair of such so functioning spheres and to produce a structure embodying all the necessary functioning features which at the same time shall obviously be useful and usable interchangeably as to the presentation thereto of a razor blade. To this end it is an objective to maintain symmetry about a median plane so that there shall be obviously no left and right hand to the structure or, in other words, so that there shall be no front or back to the structure.

Also, in carrying out the general objects of the invention, it is an objective that the frame for mounting such said two spheres shall itself have provisions for mounting on a support so as to preserve symmetry and at the same time provide adequate sustaining power.

The above and further objects of the invention will better be understood by reference to the following specification and will be pointed out in the following claims which are directed merely for purposes of illustration to an illustrative embodiment of the invention described in this specification in connection with the accompanying drawings which form a part hereof. This application is a division of my co-pending application Ser. No. 682,888, filed Dec. 27, 1923, for a blade sharpening device.

In the drawings Fig. 1 is a top plan view of the structure. Fig. 2 is a vertical cross section through the structure and Fig. 3 is an end elevation of the structure.

Referring now more in detail to the drawings, a substantially rectangular base member 1, preferably of metal, is provided with lateral enlargements or curved lateral exten-

sions 2 to accommodate one or more perforations 4 which one or more perforations are preferably located in the median plane passing between the spheres 12 and 13 and tangent thereto about which the entire structure is preferably symmetrical. The one or more perforations 4 are for the purpose of mounting suitably securing means passing therethrough into an auxiliary support in the usual manner except that it is preferred that they be located as shown in the median plane of the structure.

At the ends of the base member 1 and preferably integral therewith are two upstanding arms 6 and 7. It is preferred that the frame comprising the base 1 and arms 6 and 7 be constructed of metal and the structure may be weakened if desired by the provision of notches 8 and 9 serving to reduce the force necessary slightly to separate the said arms and the parts controlled thereby. The arms 6 and 7 sustain symmetrically positioned metal cups 10 and 11 which in turn mount a pair of similar surface hard steel spheres 12 and 13 and mount them controllably against the separating force of a razor blade engaging them at their point of tangency and against other forces such as the force of gravity acting upon the spheres. The spheres 12 and 13 are mounted in the cups so that except for friction they are permitted to roll about so that new surfaces may be presented for smoothing and sharpening the edge of a blade.

If desired anti-frictional means such as the ball bearings 14 may be interposed between each sphere and the holding surface of each cup. These cups are cylindrical in form and in the embodiment illustrated are sustained by the arms 6 and 7 by means of pointed screws 16 and 17 adjustable in the arms 6 and 7 to facilitate effecting a control separation between the cups and in consequence between the two spheres sustained by the cups. These screws may be set in adjusted position by lock nuts 18 and 19. By means of the screws 16 and 17 a nicety of adjustment of the forces tending to prevent the separation of the spheres may be effected so that when the frame is made of cast iron an adjustment may be effected to utilize the limited resilience of

cast iron without the necessity of an adjustment by bending.

What I claim and desire to secure by United States Letters Patent is:—

1. A razor sharpener structure which in its entirety is symmetrical about a median plane, comprising two surface hard steel spheres juxtaposed on opposite sides of said median plane; a pair of symmetrical cups for forcibly mounting said spheres against separating and other forces; a metal frame having a substantially rectangular base member provided with curved lateral extensions to accommodate one or more screw mounting perforations which one or more perforations are located in said median plane; two integral symmetrically spaced arms upstanding from the ends of said base member for sustaining said cups, said upstanding arms having provisions for permitting a controlled separation between said cups and in consequence between said two spheres sustained by said cups.
2. The structure as described in claim 1, further characterized by the fact that anti-frictional means in the form of small ball bearings interposed between the opposed faces of said spheres and said cups is provided.
3. A blade sharpener comprising a bracket having means by which it may be secured to a support, said bracket having raised end elements, pivot clamp screws adjustable in said end elements, locking means for said screws, cylindrical cups carried on the points of said screws, a plurality of relatively small anti-frictional spheres in said cups and a hardened sphere of relatively large diameter seated on the balls of each cup, said larger spheres being held in peripheral contact by adjusting said screws.
4. A razor sharpener structure comprising an integral metal frame having a flat base member adapted to be mounted in a horizontal position, having two integral upstanding symmetrical arms each making substantially a right angle with said base member; a pair of inwardly facing cups at the upper ends of said arms with their concave cavities facing inwardly, said base also having a perforation for the passage therethrough of attaching means located substantially in the median plane between said arms and said base also having a reinforcing enlargement at the locality of said perforation; and a pair of surface hard sharpening spheres respectively sustained by said cups, the concavities of said cups cooperating to prevent the displacement of said spheres.

JOHN HOLTZMAN.
